UNITED STATES PATENT OFFICE.

NATHANIEL J. PRITCHARD AND JAMES S. TEMPLON, OF MILNES, ASSIGNEES,
BY DIRECT AND MESNE ASSIGNMENTS, TO THE PRITCHARD BRAKE COMPANY,
OF ROANOKE, VIRGINIA.

DEVICE FOR APPLYING PRESSURE TO RAILWAY-BRAKES.

SPECIFICATION forming part of Letters Patent No. 399,159, dated March 5, 1889.

Application filed March 5, 1888. Renewed January 18, 1889. Serial No. 296,794. (No model.)

To all whom it may concern:

Be it known that we, NATHANIEL J. PRITCHARD and JAMES S. TEMPLON, citizens of the United States, residing at Milnes, in the county of Page and State of Virginia, have invented 5 certain new and useful Improvements in Devices for Applying Pressure to Railway-Brakes; and we do hereby declare the following to be a full, clear, and exact description of the invention, such as will enable others skilled in the art to which it appertains to make and use the same.

Our invention has reference to a device for use in applying pressure to pneumatic railway-brakes for the purpose of controlling and 15 regulating the admission of air to the brake-cylinder; and it consists, essentially, in the construction, arrangement, and combination of parts, substantially as will be hereinafter 20 described and claimed.

In the accompanying drawings, illustrating 25 our invention, Figure 1 is a vertical section of our improved device for applying pressure to pneumatic railway-brakes and shows the piston-valve at the upper limit of its stroke. Fig. 2 is a horizontal section on the line $x-x$ of Fig. 1. Fig. 3 is a vertical section similar 30 to that shown in Fig. 1, with the piston-valve occupying the position where air is permitted to pass into the brake-cylinder. Fig. 4 is a perspective view of the double-ended piston-valve, together with the graduating or regulating piston. Fig. 5 is a detail view showing 35 in perspective the exhaust-valve used with the piston.

Similar letters of reference designate corresponding parts in all the figures.

A represents a cylinder of any suitable dimensions and made in any desired manner, 40 it being adapted to be arranged in an upright position beneath the car with which it is used. It may be made in one or more parts, as preferred. In the drawings the preferable construction is shown, consisting of the main cylindrical body, upon the top of which is a cap-plate, A', securely bolted thereto. The bottom of the cylindrical part A is closed by means of a plate securely fastened to it and carrying a bulb-shaped air-chamber, B, which 45 is calculated to receive at its bottom any drip-

ings or other waste that may accumulate therein, whence they are removable through a drain-cock, a. The cap-plate A' is provided with a cylindrical extension, G, which projects downward for a certain distance into the 55 chamber within the main body A. The wall of the cylindrical extension G is provided near its lower circular periphery with a series of apertures or orifices, g, which may be of any number desired. It is also furnished at a suitable point adjacent to the cap-plate A' with a small port, b.

The cylinder A is provided with ports at points where the several pipes are coupled, that are used with the ordinary air-brake and 60 lead to the essential parts of the same.

Thus C denotes the port where a coupling is made with the pipe which leads to the air-drum or auxiliary reservoir.

D is the port where the pipe is connected 70 leading to the brake-cylinder.

E is a port located in a side wall of the bulb B at a point where it is entered by pipe F, that leads to the main air-supply pipe, and through said pipe F air is introduced into the 75 device.

At port D is connected a T-shaped pipe, as will be seen by reference to Fig. 2. This pipe has a horizontal portion extending outward from the cylinder A, and at right angles to 80 this horizontal portion is another horizontal part, H. At the intersection of these two parts is located a plug-valve, H', which will ordinarily be turned into the position shown in Fig. 2, where air will pass in one direction 85 or the other between the port D and the pipe I, which leads to the brake-cylinder and is coupled to one end of the pipe H.

A short distance below the port D in the wall of the main body A is located an exhaust-port, e. Through this exhaust-port the air from the brake-cylinder will have free egress when the brakes are relieved. A vertical passage, c, extends upward through the wall of cylinder A from the bottom of said cylinder to the port C. Near the bottom of the cylinder A communication is established between the interior thereof and the passage c by means of a port, d, through which air coming under pressure from the main supply- 90

is calculated to receive at its bottom any drip- 95

50

- pipe may pass on its way to the air-drum. Near the center of the cap-plate A' a port, J, opens centrally into the cylindrical extension G, and communicates with the passage f, running horizontally through the cap-plate and then through the wall of the body A, until it reaches the port D. Within the central chamber of the device is located a suitably-constructed piston. It is preferably made in the form of a double-ended piston having the lower head, L, and the upper head, M, said heads or ends being connected by rods K K. The head M is flanged circumferentially at top and bottom, or otherwise suitably fastened and shaped to afford an annular recess capable of receiving an encircling annular ring, N, made in two parts, as shown in Fig. 5, to permit its easy adjustment, said ring serving as an exhaust-valve. The ring N is loosely arranged around the piston end M. Said ring is recessed at n for a portion of its circumferential distance, said recessed portion being situated adjacent to the ports D and e, and being of sufficient size to connect said ports whenever the position of the piston, and consequently of the exhaust-valve, is such as to permit of this connection. The vertical length of the exhaust-valve is shorter than the vertical length of the annular space within which it is contained, as will be seen upon inspection of Fig. 1 or 3; hence it will be evident that the piston may have a certain amount of vertical movement without displacing the valve from its position.
- 35 The object and purpose of allowing the piston to have a movement independent of any corresponding motion on the part of the valve will be evident hereinafter. The head M of the piston is furthermore constructed in the form of a cylinder, as shown in the drawings. By making the head M of this form the piston is not only lighter, but more space is afforded for air within the chamber of body A.
- 45 The piston just described may vary considerably in the details of its structure without departing from our invention. We have aimed herein to give a general description of it without being confined to details. The piston has a vertical movement up and down within the central chamber, and in said movement it comes into proper relation to the several ports and passages hereinafore mentioned to accomplish the results which will be farther on more specifically stated. It becomes necessary, however, in order to make our device practically and effectively operative, to provide means whereby the amount of air which is admitted to the brake-cylinder may be graduated, regulated, and governed, so that the engineer may be enabled to set the brakes at a certain desired pressure and keep them at this pressure until he wishes to release them.
- 55 By the use of the piston alone just described good results may be accomplished in applying the brakes; but the engineer cannot with-

out an auxiliary device automatically measure and maintain any desired amount of pressure upon the brake. In order to do this, 70 we provide a graduating-piston, O, working within the cylindrical extension G and adapted to open and close the port b. A piston-rod, O', is connected to the piston O, and extends vertically downward, passing through a central opening in the head M of the piston, and provided on its end with an adjustable nut, P. When the piston descends from its uppermost position, the piston end M will strike the nut P and cause the piston O to descend like- 75 wise for a certain distance.

It remains to describe the operation of our improved device for applying pressure to pneumatic railway-brakes. When the main piston occupies its uppermost position, as seen 85 in Fig. 1, air can easily pass from the brake-cylinder through pipe I to the port D and around through the recess n in the encircling ring N into the exhaust e, where it will escape into the atmosphere. Air coming under pressure through the main air-supply pipe F will enter the air-chamber, pass up underneath the piston, then through the port d and passage c to the air-drum. Air will likewise, under the same pressure, be upon the top or upper 95 end of the piston, since it will pass through the apertures g in the cylindrical part G. Likewise the air will bear upon the piston O, holding it in its uppermost position, so that the port b will be closed and likewise the port 100 J. Suppose, now, that it is desired to set the brakes. The engineer will determine the amount of pressure which he desires to apply to the brakes and adjust his regulating-valve accordingly. Whether a great or less pressure is desired will of course depend upon the circumstances of each case. The proper manipulation of the engineer's valve will exhaust air from beneath the main piston of the device, so that said pressure beneath will be 105 less than the pressure above it. The piston in consequence will begin to descend. In the course of this descent the piston end M will strike the nut P and draw down the piston O, opening port b. An outlet is thus at once 115 afforded for the air-pressure above the main piston; hence the main piston will cease its further downward movement, while the air above it is rushing through the small port b into the space above the piston O, and thence 120 through port J, passage f, and pipe I into the brake-cylinder. The continued outflow of air through the small port b will in a short time cause the air-pressure in the air-drum and above the main piston to be less than the air-pressure beneath the main piston. The result of this inequality of pressures on the upper and lower ends of the main piston will be to cause the latter to adjust itself slightly; hence it will ascend a little, but not enough 125 to displace the valve N from the position shown in Fig. 3, where the port D is closed.

It has already been stated that the main piston is permitted a certain range of move-

ment without interfering with or compelling a change of position of the valve N. After the main piston has risen to the slight extent just referred to it will be evident that the 5 piston end M will no longer be in contact with the nut P, and hence the piston O will have its position regulated by the air-pressures above and below it. The air-pressure above the piston O will be less than the air- 10 pressure below it, because this pressure below is the same as that in the air-drum, and since the port b is very small a sufficient amount of air will not have passed through said port to the brake-cylinder in the short 15 interval which has elapsed since it began to flow through said port to make the pressure above the piston O counterbalance the pressure below it. It is therefore clear that the upward pressure on the piston O will lift the 20 same and close the port b, thus leaving a constant pressure applied to the brakes. The present position of all the parts will now be maintained until the engineer releases the brakes. If he has applied a ten-pound pressure 25 to his brakes, the graduating-piston, acting in conjunction with the main piston, in the manner just explained, will cause the ten-pound pressure, after it has been placed upon the brakes, to be maintained; similarly with 30 a fifteen-pound or thirty-pound pressure, according as the engineer may have adjusted his valve for the one or the other.

When it is desired to relieve the brakes, air will be admitted below the main piston, 35 driving the same upward into the position shown in Fig. 1, where the recessed ring N connects ports D and e, and enables an out-flow of air from the brake-cylinder through the exhaust.

40 Having thus described our invention, what we claim as new, and desire to secure by Letters Patent, is—

1. In a device for applying and relieving the pressure on railway-brakes, the combination of the inclosing-case having ports leading to the air-drum, main pipe, and brake-cylinder, the double-ended piston located within said case, the valve surrounding the upper end of the piston, in the manner specified, 45 and the graduating-piston, all the parts being combined and arranged for joint operation, substantially as described.

2. In a device for applying and relieving the air-pressure to pneumatic railway-brakes, 55 the combination of the cylindrical inclosing-case having ports leading to the air-drum, main pipe, and brake-cylinder, suitable air-passages, as specified, and also an exhaust-port, the cap-plate for said inclosing-case 60 having a downwardly-projecting cylindrical extension provided with a port and apertures, the main double-ended piston operating within the inclosing-case, and the graduating-piston working within the cylindrical 65 extension on the cap-plate, all substantially as described, and for the purpose set forth.

3. In a device for applying and relieving the air-pressure to air-brakes, the inclosing-case provided with properly-arranged ports, as specified, in combination with the main 70 double-ended piston, its surrounding valve, and the graduating-piston having its piston-rod connected to and actuated by the main piston, substantially in the manner and for the purpose set forth. 75

4. The combination of the inclosing-case having ports leading to the air-drum, main pipe, and brake-cylinder, together with connecting-passages and exhaust-ports, the cap-plate for said case having a downwardly-projecting cylindrical extension furnished with a small port and other apertures, the main double-ended piston carrying a valve arranged relatively thereto, as described, the graduating-piston working in the cylindrical 85 extension on the cap-plate and having its piston-rod connected to and adapted to be actuated by the main piston, all substantially in the manner and for the purposes hereinbefore described. 90

5. The combination, with the inclosing-case having ports C D E and exhaust e, the cap-plate A', having the cylindrical extension G, provided with port b, and an aperture or apertures, g, said case and cap-plate having 95 also suitable air-passages, of a main piston operating within the central chamber, and a graduating-piston operating within the cylindrical extension on the cap-plate to accomplish the result specified, substantially as set 100 forth. 100

6. The combination of the cylindrical case A, having ports C D E and exhaust e, the cap-plate A', having the extension G, provided with small port b, and an aperture or 105 apertures, g, the main piston having suitably-connected heads L and M, said head M being peripherally flanged at top and bottom to form an annular recess, the valve N, located within said annular recess, and the piston 110 O, working within the extension G and having a piston-rod, O', projected through the head M and furnished with a nut, P, all the parts being arranged substantially as and for the purpose described. 115

7. In combination with an inclosing-case constructed substantially as described, a main piston having heads L and M, said head M being annularly recessed, the valve N, recessed at n and located within the said annular recess of head M, but being shorter in vertical length than the recess, for the purpose indicated, and the piston O, having rod O', extending through head M and furnished with nut P, all substantially as described. 120 125

In testimony whereof we affix our signatures in presence of two witnesses.
